UNITED STATES PATENT OFFICE.

CHARLES L. PAULUS AND ROBERT KAUCH, OF DAYTON, OHIO.

ADJUSTABLE IMPULSE GENERATOR.

Application filed July 25, 1924. Serial No. 728,190.

This invention relates to synchronized gun controls and is an improvement on the control at present in use in which the trigger of a machine gun is synchronously operated with the speed of the engine.

The object of this invention is to provide an impulse generator for use in synchronized gun controls which incorporates means to adjust the angle of departure of the impulse cable, so that equipment on the airplane such as parts of the motor, generator, etc., may be cleared by the impulse cable casing. The impulse generator is adapted to be adjustable so that the impulse cable may be adjusted either up and down or side-ways.

Further objects will be more fully set forth in the attached specification, in the claims, and in the drawings, in which

Fig. 1 is a plan view of our improved impulse generator.

Fig. 2 is a vertical section of the same on the line 2—2 of Fig. 1.

Fig. 3 is an elevation of the impulse generator, and

Fig. 4 is a section on the line 4—4 of Fig. 3.

Referring to the drawings by reference numerals, the bevel gear 1 which is adapted to be driven from the engine shaft of an airplane is fixed to and operates an impulse shaft 2, which is provided at its upper end with an impulse cam 3 provided with two lobes 4 and 5. The impulse shaft 2 is mounted by means of ball bearings 6 and 7 in a housing 8 which extends over the top of the shaft 2 and cam 3, extending part way round the same. The housing 8 is provided with a flanged portion 9 which is provided with an outer, plane, substantially vertical face, to which a flanged portion 10 of a support casting 11 may be secured.

The support 11 forms a means of attachment of an impulse lever 12, which is pivoted on an axis 13 and provided with a curved arm 14, the end of which is located substantially at the center of the flange 10 so as to be operated by the rotation of the impulse cam 3. The opposite arm 15 of the impulse lever is attached by means of a clevis 16 to the operating cable 17, which extends to and operates the trigger of the machine gun. The cable casing 18 is held in fixed position in the end of the cylindrical extension of the support 11.

It will be understood that when the bevel gear is rotated by the action of the motor at

a constant speed, the impulse cam 3 will operate to rapidly oscillate the lever 12 about its pivot 13 so as to give a series of pulls upon the operating cable 17 to operate the cable in synchronism with the propeller, so that the gun may fire between the propeller blades. When it is desired to stop this operation, a locking pin 20 is released by releasing the pull previously maintained upon a releasing cable 21, so that a spring 22 forces the locking pin 20 into the position as shown in Fig. 2, where it engages the curve of the arm 14 so as to hold the end of this arm away from engagement with the impulse cam, and under such conditions the gun will cease firing.

The housing 8 is provided with a lower flange 23 which rests on and is adjustably secured to a base member or plate 24. The lower housing flange and the base member 24 are provided with a series of vernier holes 25 of which there are preferably two more holes in one of the members than in the other, so that a vernier adjustment may be provided by means of two bolts 26, which interconnect and detachably secure in an adjustable manner, the housing and the base member. In the drawings the housing flange is shown as provided with 18 holes, the holes being equally spaced in each member so that very small relative adjustments may be made. These adjustments permit variation in the direction in which the operating cable 17 extends away from the impulse generator horizontally.

The direction in which the operating cable 17 extends may be adjusted vertically by adjustment of the support 11 upon the flange 9 of the housing. This adjustment is permitted by a second series of vernier holes 27 and two bolts 28 which permit the support 11 to be rotated about an axis corresponding to the point where the cam operates upon the impulse lever 12, which is of course also the loci of the centers of the vernier holes 27.

The base member 24 is adapted to be secured to a fixed part of the engine frame indicated at 29 by a series of holes 30 and bolts 31. Four equally spaced holes 30 are shown in the example indicated by the drawings so that the entire unit may be lifted vertically from the part 29 of the motor and rotated thru a 90° or 180° angle in either direction so as to make adjustments in the timing of the firing of the gun, while still

permitting the vernier adjustment to vary the direction of departure of the impulse cable.

From the description of the device referred to it will be evident that it is an easy matter to adjust the direction of departure of the impulse cable from the impulse generator about a line coinciding with the axis of the impulse shaft 2 and also about an axis 10 intersecting the axis of the shaft 2 at an angle of 90°.

We claim:

1. An impulse generator comprising a housing, an impulse cam therein rotatable about an axis, an impulse lever operated by said cam, means for rendering said lever inoperative, a support for said impulse lever, and means for adjusting said support on said housing said impulse cam being housed 20 by the housing and the support.

2. An impulse generator comprising a housing, an impulse cam therein, an impulse lever operated by said cam, means for rendering said lever inoperative, a support for 25 said impulse lever, a series of vernier holes in said housing and said support, for permitting small changes of adjustment on said support.

3. An impulse generator comprising a 30 housing, an impulse cam therein, an impulse lever operated by said cam, a support for said impulse lever, means for adjusting said support on said housing, a base member, and a means for adjusting said housing on said 35 base member.

4. An impulse generator comprising a 40 housing, an impulse cam therein, an impulse lever operated by said cam, means for rendering said lever inoperative, a support for said impulse lever, means for adjusting said support on said housing, a base member, means for attaching said base member to an object, and means for adjusting the housing on said base member.

5. An impulse generator comprising a 4 housing, an impulse shaft, a cam thereon, an impulse lever having an end bearing on and operated by said cam, a support for said impulse lever, and means for quickly adjusting said support on said housing about 5 an axis passing through the point of contact of said lever on said cam, said means permitting adjustment of said support about an axis intersecting the axis of said shaft and at right angles thereto. 52

6. An impulse generator comprising a housing, an impulse shaft, a cam thereon, an impulse lever operated by said cam, a support for said impulse lever, a series of vernier holes in the support, and housing, for 60 adjustably attaching said support to said housing, said means permitting adjustment of said support about an axis intersecting the axis of said shaft and at right angles thereto, a base member, and a series of vernier holes in said base member and housing, for adjustably attaching said housing to said base member. 65

7. An impulse generator for synchronized gun control, comprising a housing, an impulse shaft therein, a cam mounted coaxially on said shaft, an impulse lever having an arm actuated by said cam, a pivot for said lever, a support for said impulse lever pivot having a plane, substantially vertical face, 75 a corresponding vertical face on said housing, means for quickly attaching and adjusting said support to said housing, said means permitting adjustment of said support about a transverse axis intersecting the 80 axis of said shaft in the cam location, and means connected to said lever to transmit impulses to a part to be controlled. 85

In testimony whereof we affix our signatures.

CHARLES L. PAULUS.
ROBERT KAUCH.
